UNITED STATES PATENT OFFICE.

RAYE E. POWER, OF FRANKFORT, INDIANA.

PHONOGRAPH SOUND BOX.

Application filed June 2, 1923. Serial No. 643,001.

This invention relates to sound boxes for phonographs, and particularly to means for mounting the needle of a sound box so as to permit free vibration thereof.

5 A further object is to provide a needle or stylus holder for sound boxes which is particularly adapted for the purpose of holding glass needles or needles of like frangible character.

10 A still further object is to provide a device of this character which does not use the ordinary set screw for the purpose of holding the stylus in place within its socket but which uses a spring clamp for this purpose so that the needle will not be subjected 15 to such strain as would be liable to break it, the device, however, being so arranged as to permit regular metal needles to be used.

Another object is to provide improved 20 means for mounting the support for the stylus bar and for the needle which will cause the proper transmission of vibration from the stylus to the stylus bar and thus to the diaphragm, and yet which is firmly 25 held in place within the sound box.

Other objects will appear in the course of the following description.

My invention is illustrated in the accompanying drawings, wherein:—

30 Figure 1 is a fragmentary front elevation of a portion of a sound box with my improved stylus mounting thereon;

Figure 2 is a side elevation of the structure shown in Figure 1;

35 Figure 3 is a top plan view of the body 22;

Figure 4 is a section on the line 4—4 of Figure 1;

Figure 5 is a cross section on line 5—5 of Figure 1;

40 Figure 6 is a fragmentary section on the line 6—6 of Figure 1.

Referring to these drawings, 10 designates a stylus supporting member which is approximately rectangular in cross section and is formed upon one face with a longitudinally extending recess constituting a socket 11 for the reception of the needle 12, one face of the member 10 being provided with outstanding ears 13. Between these 45 ears is pivoted the needle clamp 15, the lower end of which extends downward and is angularly bent and extended into the socket 11. This end 16 is recessed or slightly arcuate in form so as to embrace about one-third of the needle 12 and hold the needle firmly in 50 position. The upper end of this clamp 15

is outwardly bent and formed with a head 17 which constitutes a finger piece whereby the clamp may be opened. A V-shaped spring 18 has one leg inserted in a notch 19, 60 the other leg being disposed within a notch 20 formed in the face of the member 10, this leg of the spring being held in place by a screw 21.

The member 10 has a base which is curved 65 to approximate the curvature of the rim of the sound box and embodies the two oppositely directed, slightly curved arms 22. The inner face of this base is longitudinally grooved, as at 23, and each arm is formed 70 with an outwardly projecting ear 24, one of these ears being on the outer face of its arm and the other ear being on the inner face of its arm. These ears are perforated 75 for the passage of attaching screws 25 having heads 26, and disposed between the heads and the ears are the coiled springs 27. Resting directly against the rim of the sound box is a plate 28 having apertures larger than the screws 25 and through which the 80 screws pass. This plate bears directly against the rim of the sound box and has on it two outwardly projecting posts or studs 29 which extend into the groove 23 adjacent the ends thereof and constitute fulcrums upon which the member 10 may rock. The screws 25 have screw-threaded engagement with the sound box, and a nut 30 85 engages the screw and bears against the plate 28 to hold this plate in place. 90

Extending outward from the upper end of the portion 10 midway between the extremities of the arms 22 is an outwardly extending lug 31 which is formed integral or cast with the body 10, this lug having a 95 tapering aperture 32 extending through it parallel to the face of the member 10. The stylus arm 33 is angularly bent at one end for engagement with a diaphragm, as at 34, the opposite end of this arm being tapered 100 and inserted in the tapered socket 32 and being drawn toward the lug 31 by means of an adjustment screw 35. Preferably the body 10 with the arms 22 are cast in one piece and preferably these parts will be 105 made of blue steel or like material.

It will be seen that the springs 27 pressing against the lugs 24 urge the body 10 with its arms 22 toward the sound box and that the nuts 30 force the plate 28 110 against the periphery of the sound box. It will further be seen that by adjusting the

screws 26 that the tension of the springs may be adjusted and that the body 10 is yieldingly forced toward the periphery of the sound box and held in engagement with the lugs 29. The groove 23 and the lugs 29 are of such form as to permit the rocking of the body 10 upon these lugs 23 as upon a fulcrum. The vibrations of the diaphragm will vibrate one end of the stylus bar 33 and this vibration will be communicated through the lug 31 to the body 10 which, as before remarked, will rock upon its fulcrum and this in turn will cause the vibration of the stylus 12.

15 Preferably the needle 12 will be of glass, but I do not wish to be limited to this, as any type of needle may be used in the socket 11, but the gripping means for the stylus or needle is particularly designed for gripping a glass stylus so as not to break it. If the ordinary set screw is used such as is commonly found on phonographs, the pressing inward of the set screw would tend to break the needle. This cannot occur with 25 my holder, while at the same time the needle clamp holds the stylus firmly in place and prevents any play. By pressing upon the head of the clamp 15, the needle will drop out and a new needle may be readily inserted.

30 It will be seen that this holder fits against the periphery of the sound box and not in front of the sound box, thereby supporting the sound box better and securing a better appearance.

35 I claim:—

1. A sound box having a diaphragm and a rim, means on the sound box for supporting a stylus, said means comprising a radially extending member formed at its base with two integral laterally directed arms, and at its outer end with a stylus socket, the base being formed with a longitudinally extending groove on its inside face transversely curved and extending the full length of the base, a plate disposed against the periphery of the sound box, screws passing through the arms of said base and loosely through the plate and having screw-threaded engagement with the sound box, nuts engaging said screws and bearing against the plate, tapering lugs projecting from the plate and having their apices bearing against the grooved inner face of the plate and forming fulcrums upon which the base may rock in a plane transverse to the plane of the sound box, the groove acting to center the lugs, springs surrounding the screws and

bearing against the outer faces of said arms and yieldingly resisting rocking movement of the member, a stylus bar operatively connected to the center of the diaphragm, and a lug projecting from one face of the member with which said stylus bar engages, the opposite end of the member being provided with means for supporting the stylus.

2. A sound box having a rim and a diaphragm, means for supporting the stylus thereon comprising a radially extended member formed to provide a base having a curvature corresponding to the curvature of the rim of the sound box, this base projecting laterally on each side beyond said member to provide oppositely disposed arms, one of said arms having a lug upon one edge face and the other arm having a lug upon the opposite edge face, the inside face of the base being longitudinally grooved, the groove being transversely curved, a plate disposed against the periphery of the diaphragm and having a plurality of approximately triangular lugs extending therefrom and into said groove and acting as fulcrums, the groove acting to center said lugs and the base having rocking engagement with said lugs, nuts engaging said screws and bearing against the plates, springs surrounding the outer ends of the screws and bearing against the first named lugs on the arms whereby to yieldingly hold the base in engagement with the curved plate to permit the base to rock upon said triangular lugs, a stylus bar operatively connected to said member at one end and at its opposite end operatively connected to the center of the diaphragm and vibrating with said member, and means at the opposite end of the member for detachably holding the stylus.

3. The combination with a phonographic sound box, of a stylus carrying member oscillatably mounted upon the peripheral wall of the sound box and having an outwardly projecting lug formed with a tapered aperture, and a stylus arm engaged at one end of the sound box, the other end of the arm being tapered and disposed in said tapered aperture and fitting the same, and a screw passing through said aperture and engaging the end of the stylus arm whereby the stylus arm may from time to time be adjusted in said tapered aperture.

In testimony whereof I hereunto affix my signature.

RAYE E. POWER.
